UNITED STATES PATENT OFFICE.

JOHN K. STEWART, OF CHICAGO, ILLINOIS; JULIA B. STEWART EXECUTRIX OF SAID
JOHN K. STEWART, DECEASED.

DELIVERY MEANS FOR MELTING-POTS.

1,219,357.

Specification of Letters Patent. Patented Mar. 13, 1917.

Application filed November 20, 1915. Serial No. 62,524.

To all whom it may concern:

Be it known that I, JOHN K. STEWART, a citizen of the United States, residing at Chicago, in the county of Cook and State of Illinois, have invented new and useful Improvements in Delivery Means for Melting-Pots, of which the following is a specification, reference being had to the accompanying drawings, forming a part thereof.

10 This invention relates to melting pots, and particularly to means for discharging molten metal therefrom with special reference to the handling of aluminum and its alloys in the molten state. The invention consists of 15 the features and elements and their combinations hereinafter described and shown in the drawings as indicated by the claims.

In the drawings:

Figure 1 is a top plan view of a melting pot embodying this invention.

Fig. 2 is a vertical section taken as indicated at line, 2--2, on Fig. 1.

Fig. 3 is a transverse vertical section taken as indicated at line 3--3, on Fig. 1.

25 Fig. 4 is a transverse detail section taken at the same plane as Fig. 3, but showing the valve in closed position.

Fig. 5 is a transverse detail section taken as indicated at line, 5--5, on Fig. 2.

30 Fig. 6 is a horizontal detail section taken as indicated at line, 6--6, on Fig. 2.

In handling aluminum in molten condition considerable difficulty is experienced by reason of the basic or alkaline nature of the 35 metal as compared with the more or less acid nature of nearly all other metals, and therefore of such other metal as must be employed as a container in which the aluminum is melted and from which it is discharged 40 when cast into molds. In the die-casting process this difficulty is increased by the presence of air under pressure which is used to force the metal into the molding dies and which, according to the usual practice, is applied 45 to the entire surface of the metal in the melting pot, the latter being made substantially air-tight for the purpose; the high temperature together with the excessive oxygen present in the air under pressure seems 50 to make the chemical action between the aluminum and the metal of the melting pot and discharge valve associated therewith very rapid so that frequent replacements are necessary. By the present invention air 55 pressure on the whole body of molten metal

in the melting pot is entirely dispensed with so that the rapid oxidation of the aluminum is prevented and chemical action between the aluminum and the melting pot itself is minimized; and the only valve which ever comes 60 in contact with the molten metal is suspended normally above the level of the metal in the melting pot and is only subjected to its action intermittently.

Referring first to Fig. 2, the fire-box or 65 retort 1, is shown with the melting pot, 2, suspended within it and movably mounted within the melting pot, 2, is a substantially U-shaped conduit, 3, carried on trunnions, 3^a and 3^b, respectively, upon which it is rotatable through a limited angle for elevating its middle portion, 3^c, which is dimensioned 70 to be intermittently submerged in the molten metal indicated at 4. This submerged portion of the conduit, 3^c, has an inlet opening 75 at 5, formed in a boss, 5^a, which provides a seat for a valve, 6, suspended in the melting pot, 2, at a position above the surface of the molten metal, 4, and adapted to close the aperture, 5, when the conduit, 3, is swung to 80 the position indicated in Fig. 4. The lower end of the valve, 6, is substantially spherical in form and its upper end is spherically globular, being carried in a correspondingly formed seat at 7, so that it is self adjusting 85 to the valve seat at the opening, 5. The boss, 5^a, is surmounted by four sloping guide lugs, 5^b, which are adapted to initially engage the end of the valve member, 6, and direct it to 90 position for closing the opening, 5.

While the conduit, 3, is positioned as in Fig. 2 with its inlet opening, 5, submerged in the metal, 4, the passageway of said conduit will fill up to the level of the metal in the melting pot, 2, with a quantity of molten 95 metal sufficient for a single casting. Then if the conduit, 3, be rotated on its trunnions, 3^a and 3^b, to the position in which the opening, 5, is closed by the valve, 6, and if air pressure from the pipe, 8, be then applied to the end of the conduit passageway in the trunnion, 3^a, the molten metal therein will be discharged under pressure from the nozzle, 9, connected to the other end of the conduit passageway in its trunnion, 3^b, and said 100 metal may thus be forced into the mold or die indicated at A. It may be understood that the fire-box or retort, 1, is slidably carried on guide-bars, 10, upon which it is movable toward and from the casting die, A, 110

such movement being controlled by a cam, 11, on a power shaft, 12, said cam actuating a roller, 13, on a link, 14, connected at 14^a, to the retort, 1. The discharge nozzle, 9, is forced into contact with the die, A, by compression springs, 15, and the retort, 1, carrying with it the melting pot, 2, and discharge nozzle, 9, is retracted from connected position by the link, 14, working against said compression spring, 15.

10 The conduit, 3, is swung up to position for the closing of the opening, 5, of the passage-way by the valve, 6, by means of a link, 16, connected at its lower end to lugs, 3^a, and passing through an opening in the cover, 2^a, of the melting pot, 2, above which it is coupled to one arm of a bell crank, 17, whose other arm is attached to a link, 18, controlled by a cam, 19, also on the shaft, 12.

15 20 To avoid the necessity of absolute accuracy in the machining of these connections and to permit regrinding of the valve-seat at 5, if necessary, a certain amount of lost motion is introduced by interposing a spring, 20, between the nut, 16^a, on the end of the link, 16, and the sliding block, 21, to which the bell crank, 17, is pivotally connected at 21^a. Such connection includes a slot, 17^a, in the bell crank to permit the slight travel of the link, 16, with respect to the bell-crank when the retort, 1, is moved up toward the dies, A. The compressed air coming through the pipe, 8, is controlled by a valve, 22, whose stem, 22^a, is arranged for actuation by a third cam, 23, on the shaft, 12, operating a link, 24, which engages the head of the stem, 22^a, as most clearly illustrated in Fig. 1. Thus it will be seen that the three operations of moving the retort, 1, to bring the nozzle, 9, into connection with the die, A, swinging the conduit, 3, to position for closing the opening, 5, by the valve, 6, and introducing the air pressure by way of the valve, 22, for discharging the molten metal from the conduit passageway into the die, A, may all be accurately timed to occur in the order named and in quick succession simply by the proper setting of the three controlling cams, 11, 19 and 23, on the shaft 12. It may be understood that the shaft, 12, may be connected with any suitable source of power as through the worm gear, 25, and that its intermittent rotation may be controlled by any suitable form of clutch, not shown. The compressed

45 50 55 60 65 air connection to the trunnion, 3^a, will include any suitable form of swivel joint as indicated at 26, and it will be noticed that within the trunnion, 3^a, the conduit is formed with humped portion eccentric with respect to the trunnion itself. This provides a high point in the passage-way which will be at all times above the level of the molten metal in the conduit passageway, even when the latter is rotated up to the position indicated in Fig. 4; in fact this ec-

centric portion of the passage-way at 3^e lies in a plane which is oblique when the conduit, 3, stands in the position shown in Fig. 2, but which assumes a vertical position as shown in Fig. 5 when the conduit is rotated for closing the port, 5, so that the humped portion of the passage-way at 3^e, is then in its highest position. This serves to prevent any back-flow of the molten metal into the air passage-way even when the conduit, 3, is suddenly moved forward with the retort, 1, for making connection between the nozzle, 9, and the die, A. It is not so necessary to prevent the molten metal from running out through the trunnion, 3^a, and discharge nozzle, 9, because almost instantly after the conduit, 3, has been swung to position for elevating its contents, said contents are forcibly discharged by the air pressure admitted through the valve, 22.

70 75 80 85 90 95 100 105 110 115 120 125 130 As a result of the construction described there is almost no oxidation of the molten metal at its surface in the melting pot; from time to time the supply may be replenished by ingots inserted through a charging hole in the top of the melting pot normally closed by a cover, 27, but the main body of metal in the melting pot is never subjected to the action of the compressed air, and its chemical action on the melting pot and on the exterior of the conduit, 3, is therefore comparatively slow. Within the conduit, 3, from the intermittent nature of the action and from the fact that the air pressure is present only for the instant of discharge, the chemical action of this part of the apparatus is also much reduced with the result that replacements are much less frequent than with former constructions, and the general efficiency of the apparatus is much increased.

I claim:—

1. In a melting pot, means for delivering molten metal therefrom comprising a conduit movably mounted in said melting pot, having a port positioned to be submerged in the molten metal but adapted to be elevated out of said metal by a movement of the conduit, means for closing said port in elevated position, and means for applying air pressure to one end of the conduit for discharging its contents from the opposite end.

2. In a melting pot, means for delivering molten metal therefrom comprising a substantially U-shaped conduit supported on hollow trunnions with its middle portion dimensioned to be submerged in the molten metal, a port in said middle submerged portion of the conduit adapted to be elevated out of the metal by a partial rotation of the conduit upon its trunnions, means for closing said port in said elevated position, and means for applying air pressure to one end of the conduit for discharging its contents from the opposite end.

3. In a melting pot, means for delivering molten metal therefrom comprising a substantially U-shaped conduit supported on hollow trunnions with its middle portion dimensioned to be submerged in the molten metal, and having a port in said middle submerged portion, a valve member suspended in the melting pot above the surface of the molten metal in position for closing the said port when the latter is elevated by rotation of the conduit on its trunnions, and means for applying air pressure to the conduit for discharging its contents when the port is closed by said valve member.
4. In a melting pot, means for delivering molten metal therefrom comprising a conduit movably mounted in said melting pot, having a port positioned to be submerged in the molten metal but adapted to be elevated out of said metal by a movement of the conduit, a valve member supported in the melting pot above the surface of the molten metal in position for closing said port in its elevated position, and means for applying air pressure to the conduit for discharging its contents when said port is so closed.

5. In a melting pot, means for delivering molten metal therefrom comprising a conduit movably mounted in said melting pot, having a port positioned to be submerged in the molten metal but adapted to be elevated out of said metal by a movement of the conduit, a valve member pendulously supported in said melting pot above the surface of the metal and free to swing through a limited range in any direction away from the vertical, said valve member being positioned to register approximately with said port when the latter is elevated by a movement of the conduit, and being adapted to adjust itself by reason of its mounting so as to seat accurately over said port for closing the latter, and means for applying air pressure to said conduit for discharging its contents when the port is so closed.

6. In a melting pot, means for delivering molten metal therefrom comprising a conduit movably mounted in said melting pot, having a port positioned to be submerged in the molten metal but adapted to be elevated out of the molten metal by a movement of the conduit, a valve member and a ball-and-socket mounting by which it is pendulously suspended in the melting pot above the level of the molten metal therein in position for closing the said port when the latter is elevated by a movement of the conduit, and means for applying air pressure to said conduit for discharging its contents when the port is so closed.

7. In a melting pot, means for delivering molten metal therefrom comprising a conduit movably mounted in said melting pot,

having a port positioned to be submerged in the molten metal but adapted to be elevated out of said metal by a movement of the conduit, a valve member pendulously supported above the surface of the molten metal in said melting pot in a position to approximately register with said port when the latter is elevated, but free to swing through a limited range in any direction away from the perpendicular, sloping guiding means extending upwardly from said port for initially engaging said valve member to direct it to position for closing the port, and means for applying air pressure to the conduit for discharging its contents.

8. In a melting pot, means for delivering molten metal therefrom comprising a conduit having a port positioned to be submerged in the molten metal for admitting such metal to the conduit, a valve member adapted for closing said port but normally suspended above the surface of the molten metal in the melting pot, means for relatively moving said valve member and said conduit for closing the valve member to close said port, and means for applying air pressure to the conduit for discharging its contents when said port is so closed.

9. In a melting pot, means for delivering molten metal therefrom comprising a substantially U-shaped conduit supported on hollow trunnions with its middle portion dimensioned to be submerged in the molten metal, and with the axis of said trunnions above the surface of such molten metal, said middle portion having an inlet port for admitting the liquid metal to the conduit, a portion of said conduit in one of the trunnions being eccentric with respect thereto, said conduit being rotatable upon its trunnions to a limited angle for swinging said eccentric portion to its highest position above the level of liquid metal in the conduit, means for closing the port in such position of the conduit, and means for applying air pressure to the eccentric portion of said conduit for discharging the molten metal therefrom through the other trunnion.

10. In a melting pot, means for delivering molten metal therefrom comprising a conduit movably mounted in said melting pot, having a port positioned to be submerged in the molten metal and adapted to be elevated out of said metal by a movement of the conduit, a valve member supported in the melting pot in position to register with said port when the latter is so elevated, means for moving the conduit, comprising a linkage which includes a yielding element whereby said port and valve member are held in yielding engagement, and means for applying air pressure to the conduit for discharging its contents.

11. In a melting pot, means for delivering molten metal therefrom comprising a con-

duit movably mounted in said melting pot, having a port positioned to be submerged in the molten metal but adapted to be elevated out of said metal by a movement of the conduit, a valve member suspended above the surface of the metal in the melting pot adapted for closing said port in its elevated position, means for moving the conduit to effect such closure of the port, and means 10 for applying air pressure to the conduit for discharging its contents, together with mechanism adapted to automatically effect said operations in the order named.

12. In a melting pot in combination with 15 a mold or die, means for delivering molten metal thereto from said melting pot, comprising a conduit having a port positioned to be submerged in the molten metal, a valve member normally supported above the 20 surface of the molten metal, a discharge nozzle connecting with said conduit, means for moving said melting pot and said conduit bodily for connecting said discharge nozzle to the mold or die, means for relatively moving said conduit and said valve member for 25 effecting closure of the said port by the valve member, and means for applying air pressure to the conduit for discharging its contents through the said nozzle, together with 30 mechanism adapted for automatically effecting said three operations in the order named.

13. In a melting pot, in combination with a mold or die, means for delivering molten 35 metal thereto from said melting pot comprising a substantially U-shaped conduit supported on hollow trunnions, with its intermediate portion dimensioned to be submerged in the molten metal and having a 40 submerged port in said portion adapted to be elevated out of the metal by partial rotation of the conduit upon its trunnions, a

valve member supported in the melting pot above the surface of the molten metal in position for closing said port when the conduit 45 is rotated, a discharge nozzle connecting with the conduit at one trunnion, a valved air pipe connected to the conduit at the other trunnion, a rotary shaft and two cams thereon, together with linkage whereby said cams 50 are respectively adapted for rotating the conduit and opening the valve in the air pipe, the relative mounting of said cams on the shaft serving to properly time said portions with respect to each other. 55

14. In a melting pot, in combination with a mold or die, means for delivering molten metal thereto from said melting pot comprising a substantially U-shaped conduit supported on hollow trunnions, with its intermediate portion dimensioned to be submerged in the molten metal and having a normally submerged port in said portion adapted to be elevated out of the metal by 60 partial rotation of the conduit upon its trunnions, a valve member supported in the melting pot above the surface of the molten metal in position for closing said port when the conduit is rotated, a discharge nozzle connecting with the conduit at one trunnion, 65 the melting pot and its conduit being mounted for bodily movement to effect engagement of the discharge nozzle with the mold or die, a rotary cam shaft and three cams fixed thereon, together with linkage from said 70 cams respectively adapted for moving the melting pot, rotating the conduit and opening the valve in the air pipe, said cams being related on their shaft for timing said operations in the order named. 75

In testimony whereof I have hereunto set my hand at Chicago, Illinois, this 18 day of November, 1915.

JOHN K. STEWART.
